A. J. MACY

AUTOMATIC SAFETY LOCK FOR VAULT AND SAFE DOORS

Filed March 29, 1922

UNITED STATES PATENT OFFICE.

ALFRED J. MACY, OF CHICAGO, ILLINOIS, ASSIGNOR, BY MESNE ASSIGNMENTS, TO PRO. TEX LABORATORIES, INC., OF CHICAGO, ILLINOIS, A CORPORATION OF ILLINOIS.

AUTOMATIC SAFETY LOCK FOR VAULT AND SAFE DOORS.

Application filed March 29, 1922. Serial No. 547,615.

To all whom it may concern:

Be it known that I, ALFRED J. MACY, a citizen of the United States, and a resident of the city of Chicago, in the county of Cook and State of Illinois, have invented certain new and useful Improvements in an Automatic Safety Lock for Vault and Safe Doors; and I do hereby declare that the following is a full, clear, and exact description 5 of the same, reference being had to the accompanying drawings, and to the numerals of reference marked thereon, which form a part of this specification.

This invention relates to an auxiliary lock 15 for safes and vaults which is designed to function if the regular lock should be unlawfully tampered with.

An important object of this invention is to foil a burglar by utilizing any action in tampering with the usual combination, time, or cylinder lock, to throw an automatic emergency lock into locking position to prevent retraction of the door bolts.

A further object of this invention is to 25 provide such a lock which is adapted to be fitted to vaults and safes now in existence so that any owner or user can install this safety device to further protect the contents of said vault or safe against unauthorized 30 persons.

A further object of this invention is to allow placing the device in various locations in different installations so that even if the burglar knows of the existence of this emergency lock he cannot reach the same by drilling through the door because nothing on 35 the outside of the door shows where said device is installed, and with said device a hole would have to be located within small 40 limits to enable anyone to release said lock.

A further object is to construct such a device in such a way as to fit doors of various widths and constructions without requiring special parts for each installation.

A further object to be obtained in the construction of this device is to make it of standard parts or elements to avoid expensive special machine work of any sort.

An object consists in forming the bottom

of the gravity actuated member to prevent 50 its lodging on some obstruction in its downward path, the point thereon causing the weight to fall off such obstruction and thus complete its function.

Other and further important objects of 55 this invention will be apparent from the disclosures in the specification and the accompanying drawings.

The invention (in a preferred form) is illustrated in the drawings and thereafter 60 more fully described.

On the drawings:

Figure 1 shows a rear elevation of a vault door with the device of this invention installed thereon.

Figure 2 is an enlarged fragmentary elevation of the device shown in Figure 1 with the component parts clearly shown.

Figure 3 is a section on the line 3—3 of Figure 2.

Figure 4 is an enlarged section on the line 4—4 of Figure 2.

Figure 5 is a section along the line 5—5 of Figure 4.

Figure 6 is an enlarged section, with a 75 part in elevation, along line 6—6 of Figure 2.

As shown on the drawings:

A description of the device as installed in an ordinary vault follows, it being understood that the invention is not limited to the vault construction described and that said device may be built in a variety of ways suited to other door constructions.

In the diagrammatic view of the rear of 85 the vault door shown in Figure 1, the numeral 1 refers to a plate used as the front and principal part of the door, with a frame or casing 2 fastened to the same to hold the bolts 3 which lock the door by sliding into 90 holes in the walls of the door opening. The several bolts 3 are clamped or bolted together by bars 4 so as to slide as one piece when the door handle (not shown) is moved. In the usual construction of vault doors the 95 bars are locked in extended position by some form of tumbler, combination, cylinder, time, or similar lock 5. It is to be under-

stood that the above described construction of the door is immaterial to applicant's invention, the description being inserted to render clear the application of said invention to one particular form of door.

A device embodying the present invention is shown in detail in Figures 2 to 6 inclusive, where a weight 6 is hung from an internally threaded reel or nut 7 by a ribbon or cord 8 of some suitable material which is wound on said reel with the inner end of said ribbon or cord fastened to said reel. The reel is rotatably mounted on a threaded shaft 9 which is slidably but not rotatably supported by tubes 10 and 10', and which are secured to a plate or bracket 11. The tube 10 is preferably just long enough to contain the threaded shaft 9 and the end of a coupling 12 to connect to further lengths of tubing 13 to span the space between first length of tubing and the frame 2 in connection with an ordinary nut 14 mounted on a threaded adjusting shaft 15. The edge of the plate 11 nearest the swinging end of the door is provided with two inserted hardened points 16 as shown in the enlarged view in Figure 6, and the end of the adjusting shaft 15 is also provided with two of these points 16. The object of said points 16 is to hold the assembly in place on the door by being forced into the frame 2 by the tightening nut 14 against the last piece of tubing 13. The adjusting shaft 15 is made long enough so that in connection with two or three different lengths of stock tubing the device can be fitted to varying widths of doors without requiring special machine work for each particular installation.

In the open position the weight 6 is held up by a trigger 17 loosely mounted on a stud 18 on the bracket or plate 11, said trigger being held substantially horizontal by a fragile connection or cord 19 carried from a hole in its end to any stationary part of the lock 5. In the open position the threaded shaft 9 is retracted sufficiently to clear the bar 4 when the bolts 3 are in the retracted or unlocked position, i. e., when the door is unlocked and free to open.

The operation is as follows:

When the regular vault lock is operated in the usual fashion, applicant's emergency lock is unaffected and remains open because the cord 19 is attached to a stationary part of the lock and therefore is not disturbed. Should an attempt be made to force the regular lock or remove same by any irregular means, such as drilling or burning around it and removing the same entirely, or prying the same out or driving it in, the fragile cord 19 will be broken, releasing the trigger 17 which allows the weight 6 to drop, unwinding the cord 8 from the reel 7, thereby revolving said reel on the threaded shaft 9, projecting said threaded shaft outwards

against the bar 4, thereby temporarily locking the entire door mechanism against any possible manipulation from the outside. To enable the rightful owner of the vault or safe to gain admittance after an attempt at forcing entrance, a record of the exact position of the reel 7 should be made at the time of installation so that by measuring from the edges of the door on the outside a hole can be drilled to allow reverse rotation of the reel, which will retract the threaded shaft and allow opening of the door by the usual handle or lever.

The inherent resiliency of the flexible member 8 exerts a speeding up action on the reel 7 and thus causes the screw to be moved into locking position quicker than this could be effected by gravity alone.

Numerous variations in the arrangement of the various parts of the device will readily suggest themselves, and I therefore do not purpose limiting myself otherwise than necessitated by the prior art.

I claim as my invention:

1. The combination with vault doors and the like, including the locks therefor, of an automatic safety lock, consisting of a bracket, an adjustable tube fastened thereto, an extensible shaft adapted to engage with the locking means of said doors, when in locked position, a flexible means, a reel adapted to have said flexible means wound thereon, a weight attached to said flexible means, said reel arranged to extend said shaft when the weight is released, and means for releasing said weight when the regular lock is tampered with.

2. In a device of the class described, a door, a frame on the inside of said door, a lock for the door including bolts, an emergency lock, a bracket associated with the door, means associated with the bracket to grip one side of the door frame, an adjustable tube fastened to said bracket to span across and grip another part of said door frame, means for advancing an extension of said tube to engage the door bolts when in a locked position, and means for operating said emergency lock when the regular lock is abused.

3. In an emergency lock of the class described, a threaded shaft, a rotatable nut thereon adapted to project the shaft, a flexible cord wound upon said nut and a weight attached to said cord adapted to rotate said nut.

4. In a device of the class described, the combination of a releasable weight, means normally supporting the same, a nut rotated by the release of said weight, and a locking bar advanced by the rotation of said nut.

5. In an emergency lock of the class described the combination of a releasable weight, means normally supporting the same, means rotated by the release of said weight,

and a non-rotating bar advanced by the rotation of said means.

6. In combination with an emergency lock of the class described, gripping means adapted to hold said lock in position between the frames attached adjacent the edges of the door, consisting of hardened

points in the extremities of the lock, and extensible means on said lock adapted to force said points into the material of the 10 frames on the door.

In testimony whereof I have hereunto subscribed my name.

ALFRED J. MACY.

Certificate of Correction.

It is hereby certified that the name of the assignee in Letters Patent No. 1,551,580, granted September 1, 1925, upon the application of Alfred J. Macy, of Chicago, Illinois, for an improvement in "Automatic Safety Locks for Vault and Safe Doors," was erroneously written and printed as "Pro. Tex Laboratories, Inc.," whereas said name should have been written and printed as *Pro-Tex Laboratories, Inc.*, as shown by the records of assignments in this office; and that the said Letters Patent should be read with this correction therein that the same may conform to the record of the case in the Patent Office.

Signed and sealed this 13th day of October, A. D. 1925.

[SEAL.]

KARL FENNING,
Acting Commissioner of Patents.
